THERMIONIC TUBE

Donald K. Lippincott, Larkspur, and Herbert E. Metcalf, Walnut Creek, Calif., assignors to Heintz & Kaufman, Ltd., San Francisco, Calif., a corporation of Nevada

Application July 29, 1932, Serial No. 626,157

5 Claims. (Cl. 250—27.5)

Our invention relates to a thermionic tube having a high mutual conductance and more particularly to such a tube having a cathode interposed between an anode and control electrode, and a positively charged auxiliary electrode located in the plane of the filament. The tube is adapted to be used as an oscillator and amplifier at high frequencies for the transmission of radio information, and when so used, has a high power output.

Some of the objects of our invention are: To provide a thermionic tube having a high mutual conductance and consequent high power output; to provide a means for raising the amplification factor of a thermionic tube having a cathode interposed between an anode and a control electrode; to provide a positively charged auxiliary electrode in the plane of the cathode to raise the mutual conductance of a thermionic tube having a cathode interposed between an anode and a control electrode; and to provide a thermionic oscillator and amplifier tube of simple construction and high power output.

Other objects of our invention will be apparent or will be specifically pointed out in the description forming a part of this specification, but we do not limit ourselves to the embodiment of our invention herein described, as various forms may be adopted within the scope of the claims.

In the accompanying drawing forming a part of this specification, illustrating a preferred embodiment of our invention,

Figure 1 shows an exterior view of the invention.

Figure 2 is a longitudinal sectional view showing the positioning of the elements of the tube.

Figure 3 is a cross sectional view taken in the plane indicated by the line 3—3 in Figure 2.

Figure 4 is a schematic diagram, reduced to its lowest terms, showing a circuit in which the tube may be used.

Thermionic tubes having a cathode interposed between a control electrode and an anode are very satisfactory converters at high frequencies, due to the fact that the cathode acts as a grounded shield between the two electrodes and the control electrode-anode capacity is thereby greatly reduced. If an attempt is made to carry this effect too far, however, the cathode shielding greatly reduces the amplification constant of the tube.

Our invention comprises, in its broadest terms, a thermionic tube having a cathode located between a control electrode and an anode, and an auxiliary electrode in the plane of the filament

energized at a potential less positive than the anode. The emission from the cathode is thereby brought under greater control, and the amplification constant and mutual conductance is raised.

In the several figures, showing a specific form of the invention, a bulb 1 of heat-resistant glass, is provided with control electrode stems 2 and anode stems 3. Anode support leads 5 are passed through the end of the stem at an anode seal 6 forming an air-tight joint.

The anode support 5 is inserted into a yoke 7 locked on securely by a nut 8. An anode body 9 is provided with a stiffening rib 10 securely welded to its major plane surface and the outward flanges 11 of this rib slidably cooperate with arms 12 of the yoke. A pin 14 passes through both the arms and the flanges, is secured by the lock-nut 15, and the anode body is thus firmly supported.

While not shown in the drawing, there are two of these support assemblies, one for each stem, located near the upper and lower borders of the anode.

The anode is made rigid on the edges by stiffening flanges 16. The material of the complete assembly may be of some refractory metal easily degassed in vacuo, such as tantalum or tungsten.

The control electrode 17 is identical in size, shape and support, with the anode, being held securely in place by the support 19, yoke 20, rib 21, and pin 22. Flanges 24 stiffen the edges.

The open end of the bulb is provided with a re-entrant stem 25 having cathode leads 25' sealed through a press 26 which also supports the dummy wires 27 and 28 on the outside of the cathode leads, and the two ends 29 and 30 of a hairpin shaped wire 31. The two dummy wires 27 and 28 extend above the top of the anode and control electrodes and are inserted into a filament support bridge 32 of isolantite or lava, a good insulator under vacuum and heat conditions. Holes 34 and 35 are bored in the bridge, a compound filament hook 36 inserted, and springs 37 and 38 are slipped over the hook ends and fastened by the welds 39 and 40.

A filamentary cathode 41 is fastened to the cathode leads by welds 42 and 44, looped over the bends 45 and 46 in the compound hook, being maintained in position by the tension of the springs. The top portion 47 of the hairpin is arranged to clear the cross portion 48 of the filament, and the straight portions of the filament are adjusted to be parallel and in the plane of the up-

right portions of the wires 27, 28, and 31. The cathode and the coplanar wires are offset toward the control electrode so that they are closely adjacent to the control electrode.

- 5 Near the point where the wires emerge from the press, electrical conducting jumpers 48 and 49 connect wires 27 and 28 with the hairpin 31. Jumper 49 is extended downwardly by a bend 50 and connected to a lead 51 by a flexible connection 52. The lead 51 is sealed through the envelope in the usual manner.

It will be noted that the wires 27, 28, and the hairpin 31 are all electrically connected, and together constitute an auxiliary electrode lying in the plane of the cathode which may be energized through the lead 51.

After all assembly and adjustment has been made as described, the complete tube is evacuated and sealed in the usual manner. Connection caps 20 52 are applied to the anode and control electrode stems 2 and 3, held in place by cement 54, and electrically connected to the support leads by a weld 55 as shown in Figure 3. A base may be used around the lower part of the tube if desired.

25 One circuit in which the invention may be utilized is shown diagrammatically and reduced to its lowest terms in Figure 4. Here, the complete auxiliary electrode is designated by the numeral 56.

30 An input circuit, represented by lines 57 and 58, is connected to the control electrode 17 and the cathode 41. The anode, or output circuit starts at the cathode, passes through a source of potential 59, the positive end of which is connected to the

35 anode 9 through the primary 60 of an output transformer 61. It is customary to shunt this primary, particularly in radio frequency circuits, by a condenser 62. The auxiliary electrode 56 is connected to the potential source 59 at a point 64 less positive than the anode, and is connected to the cathode through a grounding capacity 65, which places the auxiliary electrode at the same radio frequency potential as the cathode, while the connection to the potential source provides a steady 40 45 positive bias.

The path of the electrons in a tube having a cathode only, interposed between anode and control electrode, is largely at right angles to the control electrode, and the emitting wires of the cathode shield a large number of electrons from the action of the control electrode, being directly interposed. However there is a small normal divergence of the stream as it passes to the anode, due to the mutual repulsion of the negative 50 55 charges, so that the electrostatic field of the control electrode passes between the cathode wires and affects a certain portion of the emission.

There is, however, a substantial part of the emission which the control field cannot reach, and which passes directly to the plate. A low amplification constant results.

When a positive potential is placed on the auxiliary electrode in the tube of our invention, the electron path is widened, as shown diagrammatically in Figure 3, and the electrons are brought into the space between the filament wires. Here the control electrode may act on them, and a rela-

tively small number of them reach the plate without being controllable.

Changing the angular path thus results in greatly increased control, an increased amplification constant, and a higher mutual conductance. 5

As the auxiliary electrode is grounded through the condenser 65, the combination of the filament and auxiliary electrode is an effective R. F. shield.

The combined actions results in a tube having a low control electrode-anode capacity, combined with a high mutual conductance and consequent power output, especially at high frequencies. 10

We claim:

1. A thermionic tube consisting of an envelope, a pair of electrically separate, opposed, planar and parallel electrodes mounted therein, a plurality of parallel rods occupying a plane intermediate the planes of said electrodes and parallel thereto, said rods being spaced to provide an aperture extending across one dimension of said 20 plane, and a filamentary cathode positioned in said aperture, in the same plane as said rods and parallel therewith.

2. A thermionic tube consisting of an envelope, a pair of electrically separate, opposed, planar and parallel electrodes mounted therein, a plurality of parallel rods occupying a plane intermediate the planes of said electrodes and parallel thereto, said rods being spaced to provide an aperture extending across one dimension of said 30 plane, a filamentary cathode positioned in said aperture, in the same plane as said rods and parallel therewith, and means for making electrical connection from outside said envelope to all of said rods. 35

3. A thermionic tube consisting of an envelope, a pair of electrically separate, opposed, planar and parallel electrodes mounted therein, a plurality of parallel rods occupying a plane intermediate the planes of said electrodes and parallel 40 thereto, said rods being spaced to provide an aperture extending across one dimension of said plane, a filamentary cathode positioned in said aperture, in the same plane as said rods and parallel therewith, an insulating bar supported by 45 certain of said bars, and resilient means mounted on said bar for tensioning said cathode.

4. A thermionic tube consisting of an envelope, a pair of electrically separate, opposed, planar and parallel electrodes mounted therein, a grid 50 having apertures therein occupying a plane intermediate and parallel to the planes of said electrodes, said apertures extending substantially across one dimension of said electrodes, and a filamentary cathode disposed in said apertures 55 in the plane of said grid.

5. A thermionic tube consisting of an envelope, a pair of electrically separate, opposed, planar and parallel electrodes therebetween, and a plurality of spaced parallel conductors occupying 60 a plane intermediate the planes of said electrodes and parallel thereto, alternate conductors only being electron emitting, said conductors being free from physical and electrical contact during the major portion of their extent between said 65 electrodes.

DONALD K. LIPPINCOTT,
HERBERT E. METCALF.
